UNITED STATES PATENT OFFICE.

PETER L. JENSEN, OF ALAMEDA, CALIFORNIA, ASSIGNOR TO KARL K. JENSEN, OF PIEDMONT, CALIFORNIA.

MAGNET.

Application filed October 26, 1927. Serial No. 228,807.

My invention relates to magnetic sound reproducers, and particularly to those of the electro-dynamic or moving coil type.

An object of my invention is to produce 5 an intense and uniform magnetic field in which to suspend the coil.

Another object of my invention is to produce such a field with a minimum of exciting energy.

10 A further object of my invention is to provide a magnet having an annular air gap of uniform and accurate dimensions.

A still further object is to provide a ready 15 means of adjusting and equalizing such an air gap.

My invention possesses other objects and valuable features, some of which will be set forth in the following description of 20 my invention which is illustrated in the drawings forming part of the specification. It is to be understood that I do not limit myself to the showing made by the said 25 description and drawings, as I may adopt varying forms of my invention within the scope of the claims.

Referring to the drawings:

Fig. 1 is a sectional view of a loud speaking telephone embodying my invention in a preferred form. The plane of section intersects 30 the longitudinal axis of the device.

Fig. 2 is a fragmentary view, partly in section, showing the use of the annular gage in adjusting the air gap.

Broadly considered, my invention comprises 35 a magnet having pole pieces which are so disposed as to form an air gap between them. The portions of the magnet carrying the two pole surfaces are mutually slidable to vary the configuration of the 40 gap, and once adjusted, may be clamped to prevent further relative movement.

Sound reproducers of the electro-dynamic or moving coil type comprise a magnet which provides a powerful magnetic field. 45 Lying within this field, and at right angles to the lines of force forming it is suspended a coil which carries the telephonic current representing the sound to be reproduced. This telephonic current sets up a magnetic field of its own, which reacts with the main field to urge the coil in a direction normal to both field and coil.

If the coil be fixed to a suitable radiating system its energy will be delivered to the 50 air. The design of such a device is directed

to the end that this energy be so delivered as efficiently as possible, and that it follow, as closely as may be, the exact wave form of the electrical energy supplied.

The force acting on the coil at any instant is proportional to the product of the constant field times the current in the movable coil. It is evident therefore that other things being equal, the sensitivity of the device is directly dependent upon the 60 strength of the field.

If the magnet is properly designed only a very small proportion of the magnetomotive force is expended in the ferro-magnetic portions of the circuit, the major part of 70 the force going to maintain the field in the air gap.

The magnetomotive force necessary to produce a given strength of field in the gap is directly proportional to the gap length. 75 It can therefore readily be seen that it is desirable to make the part of the gap not actually occupied by the coil, just as short as possible, i. e., to reduce clearances to a minimum. At the same time the coil must 80 be wholly free from the sides of the gap, for friction at this point will produce serious distortion if it does not entirely prevent the reproducer from functioning. Hence a reproducer of this character, to be commercially practical, must be so designed that the parts may be held to tolerances of the order of one thousandth of an inch, and means must be provided for accurately positioning coil and air gap so that the coil is freely 85 movable in its designed direction of motion, but is positively prevented from motion in other dimensions. How I accomplish this in a preferred embodiment of my invention will now be set forth in detail.

The main or constant field is provided by a winding 6 which I have shown insulated from a brass bobbin 7 by a layer 8 of fibrous material. Surrounding the winding is the ferro-magnetic casing 9, provided at its lower end with the inwardly projecting flange 11 which constitutes one portion of the yoke. A plate 12 constituting the remainder of the yoke is attached to the flange by the screws 13 which are threaded into the 90 flange. The holes in the plate thru which these screws pass are sufficiently large to allow an adjusting movement of the plate in its own plane of several thousandths of an inch when the screws are loose.

Riveted or otherwise rigidly fixed to the plate 12 is the core 14 which is loosely encircled by the flange 11 and projects completely thru the coil. The free end of this core or stud forms one of the pole pieces defining the air gap. The other pole piece is formed by the ring 16 which is accurately positioned on the casing by a groove or rabbet formed in its periphery.

10 A frame 17, preferably of cast aluminum, is secured to the ring pole piece by the screws 18. Lugs 19, cast integral with the frame are fastened to the brackets 21 by the screw 22, and the brackets, in turn, are 15 screwed to the casing, thus holding the pole piece, together with the frame and the parts attached thereto, firmly in place. It is advantageous to have the screws 23, which secure the brackets to the casing, pass completely thru the latter, and impinge upon the flange of the bobbin 7, thus preventing it from shifting in shipment or otherwise.

20 Mounted upon the frame are the movable elements of the reproducer. These comprise the coil 24 which is wound upon and cemented to the form 26. This form may be turned from a suitable material such as bakelite or wound from paper, with a thickened portion provided at its outer end. The conical diaphragm 27 is truncated and is serrated from the plane at which its inner diameter is equal to the outer diameter of the form, the serrations being bent outward to form a projecting flange which embraces 25 and conforms to the thickened portion of the form.

25 Over the junction thus formed is pressed a spider 28 which comprises a collar with projecting spiral spokes. The spider preferably is punched from thin sheet metal, the portion forming the collar being drawn perpendicular to the plane of the spokes. Before assembly the adjacent surfaces of collar, form and diaphragm are coated with lacquer or cement, which holds the parts permanently in place.

30 The spider is secured to the frame by screws 29 passing thru the outer ends of the spokes and clamping them between the washers 31, which are preferably of fibrous material. The leads from the coil 24 are secured to the spokes, preferably by cementing them thereto between layers of thin insulation, this construction preventing the breakage 35 of the leads from the constant vibration to which they are subjected, which is a serious source of failure in reproducers of this type.

35 Suitable means are provided at the distal portion of the frame 17 for flexibly supporting the diaphragm 27. Since this is no part of the present invention, it need not be shown or described herein.

40 The construction just described permits the ready and accurate positioning of all of the parts. The magnet structure is first assem-

bled without the diaphragm or moving parts. All of the screws fastening the assembly are set up tightly with the exception of the screws 13, which are left loose. The annular gage 32 is then slid over the stud pole piece and into the orifice of the ring pole piece, the yoke portions 11 and 12 sliding to allow the stud to center accurately to permit this. Screws 13 are then tightened and the gage withdrawn.

45 The ring pole 16 and frame 17 are drilled in jigs, so that when the spider 28 is screwed in place the coil 24 is centered in the gap without further adjustment. The spokes of the spider, being spirally disposed, allow a 50 considerable movement of the coil thru the gap, but effectually prevent motion across the gap which would permit the coil to strike the pole pieces.

55 It is of course to be understood that in claiming the magnetic circuit comprising the stud pole 14, yoke 11, 12, casing 9 and ring pole 16 as being ferro-magnetic I do not limit myself to iron, but include any of the metals or alloys having a permeability materially higher than air.

60 I claim:

1. An electro-magnet comprising a winding, a ring pole piece adjacent the winding, and a stud pole adjacent the winding and projecting into the ring pole piece, said pole pieces being mutually slideable for varying the gap between their adjacent faces.

65 2. An electro-magnet comprising a winding, a ring pole piece adjacent the winding, a stud pole adjacent the winding and adjacent the ring pole piece, and mutually adjustable yokes upon which the pole pieces are mounted.

70 3. A magnet comprising a ring pole piece, and a stud pole piece projecting into the ring pole piece, said pole pieces being mutually slideable for varying the gap between their adjacent portions.

75 4. An electro-magnet comprising a winding, a stud pole piece within the winding, a ring pole piece adjacent one end of the winding and surrounding a portion of the stud pole piece, a casing surrounding the winding and carrying the ring pole piece, and a yoke fixed to the stud pole piece and adjustable on said casing to vary the configuration of the gap between the pole pieces.

80 5. An electro-magnet comprising a winding, a stud pole piece within the winding, a ring pole piece adjacent one end of the winding and surrounding a portion of the stud pole piece, a casing having an internally extending flange and surrounding the winding and carrying the ring pole piece, and a yoke fixed to the stud pole piece and adjustable on said flange to vary the configuration of the gap between the pole pieces.

6. A magnet comprising a casing carrying a pole piece, a second pole piece within the casing, and means external to the casing for varying the configuration of the gap between said pole pieces transversely of said casing.
7. A magnet comprising a casing, a ring pole piece mounted on the casing, a stud pole piece within the casing, and means external to the casing for varying the configuration of the gap between said pole pieces transversely of said casing.
8. An electro-magnet comprising a winding, a stud pole piece within the winding, a ring pole piece adjacent one end of the winding and surrounding a portion of the stud pole piece, a casing having a flange and surrounding the winding and carrying the ring pole piece, and a yoke fixed to the stud pole piece and adjustable on said flange to vary the configuration of the gap between said pole pieces.
9. An electro-magnet comprising a winding, a stud pole piece within the winding, a ring pole piece adjacent one end of the winding and surrounding a portion of the stud pole piece, a casing surrounding the winding and carrying one of said pole pieces, the other of said pole pieces being adjustable on said casing to vary the configuration of the gap.
10. An electro-magnet comprising a winding, a stud pole piece within the winding, a ring pole piece adjacent one end of the winding and surrounding a portion of the stud pole piece, a casing surrounding the winding and carrying one of said pole pieces and having a flange on which the other of said pole pieces is adjustable to vary the configuration of said gap.

In testimony whereof, I have hereunto set my hand.

PETER L. JENSEN.
